Primary Examiner — Steven J Czyz(74) *Attorney, Agent, or Firm* — Mitchell Law PLLC; Matthew W. Mitchell(57) **CLAIM**

The ornamental design for lettered box table set, as shown and described.

DESCRIPTION

FIG. 1 is a front perspective view of a letter "A" of the lettered box tables showing my new design;

FIG. 2 is a front view thereof;

FIG. 3 is rear view thereof;

FIG. 4 is a top plan view thereof; and

FIG. 5 is a left-side view thereof;

FIG. 6 is a right-side view thereof;

FIG. 7 is a front perspective view of a letter "B" of the lettered box tables, showing my new design;

FIG. 8 is a front view thereof;

FIG. 9 is a front perspective view of a letter "Y" of the lettered box tables, showing my new design; and,

FIG. 10 is a front view thereof.

The broken lines depict portions of the article that form no part of the claimed design.
